UNITED STATES PATENT OFFICE.

WILLIAM B. FLEMING, OF LOS ANGELES, CALIFORNIA.

REGULATOR FOR MUSICAL INSTRUMENTS.

No. 910,053.

Specification of Letters Patent.

Patented Jan. 19, 1909.

Application filed July 28, 1904. Serial No. 218,550.

To all whom it may concern:

Be it known that I, WILLIAM B. FLEMING, a citizen of the United States, residing at Los Angeles, in the county of Los Angeles and State of California, have invented new and useful Improvements in Regulators for Musical Instruments, of which the following is a specification.

My invention relates to mechanical musical instruments in which a plurality of perforated music sheets are used and more particularly to organs provided with a number of manuals where it is necessary to use a separate music sheet for each manual; and the object thereof is to produce a mechanism which will enable two or more perforated music sheets, each operating a separate and independent part of an organ, to run synchronously so that all the parts will play together. I accomplish this object by the mechanism described herein and shown in the accompanying drawings, in which:—

Figure 1— is a perspective view of a tracker board for two manuals provided with my improved regulating device. Fig. 2— is a section on the line 2—2 of Fig. 1, other parts being in elevation. Fig. 3— is a section on line 3—3 of Fig. 5. Fig. 4— is a section on line 4—4 of Fig. 3. Fig. 5— is a section on line 5—5 of Fig. 3. Fig. 6— is a diagrammatic view of the electrical circuit of the regulator.

In the drawings 5 and 6 designate the side pieces of the frame which are secured to a base 7, both being preferably of hard wood for the purpose of insulating the various parts and contacts placed thereon. In these side pieces are mounted the upper and lower music drums 8 and 9 which carry perforated music sheets 10 and 11. The upper and lower take-up rolls 12 and 13 receive the music sheet as fast as it is played, and as they revolve the music is wound thereon and unwound from the music drums. The take-up rolls are provided with gears 14 and 15, respectively, which mesh with pinions, one of which 16 is shown in Fig. 2.

The mechanism so far explained is of ordinary construction, such as that described in my Patent No. 659,442 of October 9th, 1900.

Pinion 16 is mounted upon shaft 17 which passes through side pieces 5 and 6 and is provided with a metallic disk 18 adjustably secured upon the shaft by screw 19 (see Fig. 2). In the periphery of this disk is adjust-

ably secured a detent finger 20 which is adapted to pass between teeth 21 on the periphery of a drum 22 slidably mounted upon shaft 17. The inner end of the hub 60 of this drum is chambered at 23 for the reception of a coiled spring 24 which normally keeps drum 22 at such distance from disk 18 that detent finger 20 will not engage the teeth 21 thereof. Drum 22 is provided with 65 sprocket teeth 25 over which chain 26 passes connecting with sprocket wheel 27 mounted on driving shaft 28 to which power is applied to drive the apparatus.

Within drum 22 and rigidly secured thereto is a double electro-magnet 29 which, when energized as hereinafter explained, attracts disk 18 so that the drum 22 is drawn along the shaft against the pressure of spring 24 to a point where teeth 21 are engaged by 75 finger 20, thereby rotatively locking the drum to shaft 17. Upon the outer end of drum 22 is a bushing 30 of insulating material, upon which is mounted a contact ring 31 to which one end of the winding 32 of 80 the magnet is secured, the other end being grounded on the drum. A contact 33 is secured to a rod 34 mounted in socket 35 which is secured to side piece 5. This socket is connected by wire 36 with binding post 37 secured to the frame 38 of exhaust wind box 39. Binding post 37 is connected by wire 40 with collar 41 mounted upon stem 42 which rests upon pneumatic 43 within exhaust wind box 39. Stem 42 carries a metallic disk 44 adapted to engage spring contacts 45 and 46 when the pneumatic 43 is collapsed. These contacts are secured to casing 38, being connected together by a short length of wire and to battery 47 by wire 48. 95 The other pole of battery 47 is connected by wire 49 to binding post 50 secured to side piece 5 and on which is pivotally mounted a metallic bar 51 to which is secured a brush contact 52 adapted to engage disk 53. This 100 metallic bar is connected by wire 54 with a similar metallic bar 55, which last bar carries a brush contact 55' resting upon disk 18. The above mentioned disk 53 is an exact counter-part of disk 18 and is locked to its 105 shaft by a second set of magnets 29 to drive the lower take-up roll 13. Bar 55 is pivoted at 56 to a bearing 57 secured to side piece 5, carries a brake block 58 and is connected by rod 59 with pneumatic 60 which 110 is connected by air duct 61 with channel 62 in the casing of the exhaust wind box 39.

This channel opens into a chamber 63 which is in communication through port 64 with the interior of box 39 and with the outer air through port 65. Stem 42 passes through this chamber and through these ports, and carries within chamber 63 a valve 66 controlling port 64 and a valve 67 controlling port 65. Pneumatic 43 has a channel 68 which leads from its interior through the 10 casing 38 and is connected at the top thereof through ports 69 and 70 to the atmosphere. Ports 73 and 74 connect channel 68 with the interior of box 39. Passing through the casing of box 39 is a stem 75 which rests upon 15 the movable leaf of pneumatic 76. This stem carries valve 77 which is adapted to control ports 69 and 70, and valve 78 which is adapted to control ports 73 and 74. Pneumatic 76, which I will call the primary pneumatic, is connected by tube 79 with duct 80 of the tracker-board 81.

Within the exhaust wind box 39 is a secondary pneumatic 72 which is provided with a channel 72' similar to channel 68, which 25 channel opens into exhaust wind box 39 through ports similar to those provided for a channel 68. These ports are controlled by valves of a similar character operated by a primary pneumatic 76'' similar to pneumatic 76, said primary pneumatic being connected by channel 72'' and tubes with tracker duct 96 of tracker board 81 in the same manner as pneumatic 76 is connected to duct 80 of said tracker board.

35 Within box 39 is a secondary pneumatic 82 which is similar in construction and connections to the secondary pneumatic 43 before described and carries a stem similar to stem 42 carrying valves and contacts of the 40 same construction and operation as the valves and contacts of stems 42. Collar 83 corresponding to collar 41 is connected by wire 84 with socket 85 carrying an adjustable rod 86 to which is secured a contact 45 87 engaging contact ring 88 of the lower music roll mechanism, which is a duplication of the upper roll mechanism as before described, the sprocket of said mechanism being operated by chain 89 which passes over 50 the sprocket 90 affixed to shaft 28. Wire 48', corresponding to wire 48 of the pneumatic 43, leads from the contacts of secondary pneumatic 82 and connects with wire 48. Pneumatic 82 is provided with a channel 91 in all 55 respects similar to channel 68 of pneumatic 43 and the ports through which said channel is connected with the interior of box 39 and the external air are governed and controlled by valves operated by a primary pneumatic 60 76' similar in all respects to primary 76, except that such primary pneumatic is connected by a channel 91' and tubes with duct 92 of tracker-board 93 of the lower music roll mechanism.

65 Within box 39 is a secondary pneu-

matic 94 which is provided with a channel 94' similar to channel 68, which channel opens into box 39 and into the open air through ports similar to those provided for channel 68, which ports are controlled by 70 valves of a similar character operated by a primary pneumatic 76''', similar to pneumatic 76, except that said primary pneumatic is connected by channel 94'' and tubes with tracker duct 95 of tracker-board 93 in 75 the same manner as pneumatic 72 is connected by channels and tubes with duct 96 of tracker-board 81. Pneumatics 72 and 94 carry arms 98 and 99 which support and carry a stem 100. This stem carries valves 80 101 and 102, shown in dotted lines in Figs. 3 and 4. These valves are located in chamber 103 which is connected by channel 104 shown in dotted lines in Fig. 3 with the interior of pneumatic 105, the movable leaf 85 of which carries an arm 105' through which the stems carried by pneumatics 43 and 82 pass. Chamber 103 is connected with the interior of exhaust wind-box 39 through port 111, which port is controlled by valve 101, 90 and with the exterior air through port 108, which port is controlled by valve 102 shown in dotted lines. A spring 109 bears upon a button 110 to normally keep the valve 101 on its seat. The tension of this spring is 95 such that neither of pneumatics 72 and 94 have sufficient power to overcome the tension of this spring to unseat the valve 101, but when both act together they have sufficient power to overcome the tension of this 100 spring and to unseat valve 101 and seat valve 102 thereby putting pneumatic 105 in communication with the exhaust wind box 39. Pneumatic 105 is thereby collapsed and has power sufficient to hold pneumatics 43 105 and 82 from being operated or to collapse either of said pneumatics if inflated.

The music sheets are provided with short perforations 106 and 106' which are adapted to register with tracker-ducts 80 and 92 110 as the sheets travel and also provided with elongated perforations 107 and 107' which extend beyond the extremities of the short perforations 106 and 106' as shown, and are adapted to register with tracker-ducts 95 115 and 96 as the sheets travel. When the upper and lower music rolls are traveling properly these elongated perforations 107 and 107' register with the tracker ducts 95 and 96 thereby permitting the air to enter the 120 tubes which lead to the primary pneumatics that control the admission of air into secondary pneumatics 72 and 94. These pneumatics are thereby permitted to expand, which carries valve 101 off its seat and valve 125 102 onto its seat and puts pneumatic 105 in communication with exhaust wind box 39, thereby collapsing said pneumatic, which through its arm 105' holds pneumatics 43 and 82 from expanding when the short per-

forations 106 and 106' register with tracker-ducks 80 and 92, and the circuits therefore remain closed. Now should one of the music rollers, say the upper, be in advance in its 5 travel over that of the lower, when the elongated perforation 107 registers with tracker-duct 96 the primary pneumatic connected therewith will expand and open the channel which leads into pneumatic 72. As before 10 stated, the power of pneumatic 72 is not sufficient to raise stem 100 against the tension of spring 110, and the sheet continues to move until perforation 106 registers with duct 80. This admits air into the primary 15 pneumatic connected therewith, opening the channel which leads to pneumatic 43 to the open air, and closing it to the suction box, thereby permitting said pneumatic to expand and carry contact 44 from engagement 20 with the contact springs 45 and 46. The circuit is thus broken and magnet 29 is de-energized, spring 24 then pushing teeth 21 from engagement with finger 20 and the revolution of disk 81 and shaft 17 stops, but 25 the sprocket wheel 22 still continues to revolve.

In order to more positively insure the stoppage of the revolution of shaft 17 I have provided a brake-block 58 which is secured 30 to bar 55 to engage disk 18. This bar is connected by rod 59 to the movable leaf of pneumatic 60, which pneumatic is connected by tube 61 with channel 62 so that when pneumatic 43 is expanded said channel is in 35 communication with exhaust box 39 and pneumatic 60 collapses and draws the brake-block into engagement with the disk and thereby prevents its rotation. As shaft 17 operates the take-up roll, as soon as its 40 movement ceases the take-up roll and the upper music roll become stationary. As soon as the elongated perforation 107' of the lower music roll registers with tracker-duct 95 the air passes through said duct into the 45 primary pneumatic which controls the admission of air into the channel leading to pneumatic 94 thereby opening said channel to the outer air and permitting the air to enter said pneumatic and the same to expand, thereby adding its power to the power 50 of pneumatic 72. The combined power of these pneumatics overcomes the tension of spring 110 and puts pneumatic 105 in communication with the exhaust wind box, causing its collapse. Arm 105' forces pneumatic 55 43 to its collapsed position and brings contact 44 into engagement with contact springs 45 and 46 which reestablishes the circuit and again energizes the magnet to overcome the 60 resistance of spring 24, and teeth 21 are again brought into engagement with finger 20 and the revolution of shaft 17 again commences. As soon as the perforations 107 and 65 95 and 96, spring 112 restores pneumatic 105

to its normal condition and at the same time a like spring (not shown) in pneumatic 60 restores said pneumatic to its normal condition which carries the brake-block out of engagement with the disk. A like effect will 70 be produced if the lower music roll is traveling in advance of the upper one, the lower roll being braked by the action of pneumatic 60' connected by duct 61' to the secondary pneumatic in a manner similar to that in 75 which pneumatic 60 is connected to the primary pneumatic. It will be understood that these elongated perforations extend a sufficient distance beyond the extremities of the short perforations 106 and 106' that 80 when a sheet is stopped it will be started again by the time the short perforation in the traveling sheet registers with its appropriate duct.

If desired the primary pneumatics can be 85 dispensed with and the secondary pneumatics may be connected with the proper ducts in the tracker-board as described in my Patent No. 659,442 of date October 9th, 1900, but I prefer their use as thereby a much quicker 90 and more perfect action of said secondary pneumatics is obtained.

Having described my invention what I claim as new and desire to secure by Letters Patent is:—

1. In a regulator for musical instruments, two independently traveling music sheets; each provided with perforations arranged in pairs consisting of a long and a short perforation; a take-up roll for each of said 100 sheets; a clutch mechanism connected with each of said take-up rolls, said clutch mechanism consisting of a shaft; a sprocket wheel revoluble upon said shaft; an electro-magnet secured to said wheel; a metallic disk secured to said shaft and forming an armature for said electro-magnet; a spring on said shaft between said disk and wheel and adapted to keep them separated when the electro-magnet is inert; a battery; an electric 105 line having two stationary contacts therein connecting one pole of said battery to said electro-magnet; a second electric line connecting the other pole of said battery with said electro-magnet; a movable disk between 110 said stationary contacts; pneumatic means for controlling said movable disk whereby the circuit through said electro-magnet is made and broken; and means to operate said 115 sprocket wheels.

2. In combination a perforated music sheet provided with perforations arranged in pairs consisting of an elongated and a short perforation, said elongated perforation being arranged to project beyond the extremities of the short perforations; a tracker-board over which said music sheet is arranged to travel, said tracker board having ducts with which said elongated and short perforations register; a suction air cham- 130

ber; pneumatics in said air chamber into which said ducts open; a metallic disk operatively connected to one of the pneumatics by a stem projecting through the walls of said air chamber; a pneumatic without said air chamber; an arm on said exterior pneumatic adapted to engage the stem which carries the disk and prevents its movement when said exterior pneumatic is collapsed; a channel connecting said exterior pneumatic with said air chamber and with the exterior air; valves operatively connected with the other pneumatic within said air chamber adapted to govern the communication of said exterior pneumatic with the air chamber and exterior air; a take-up roll; a clutch mechanism consisting of a sprocket wheel revoluble upon a shaft; an electro-magnet connected to said wheel; a shaft on which said sprocket wheel is revoluble; a metallic disk secured to said shaft and forming an armature for said electro-magnet; a spring on said shaft between said disk and wheel adapted to keep them separated when the electro-magnet is inert; a pinion on said shaft; a gear on the take-up roll meshing with said pinion; a battery; an electric line having two stationary contacts therein connecting one pole of said battery to said electro-magnet, said contacts being adapted to be engaged by the disk carried by the pneumatic in the air chamber; a second electric line connecting the other pole of said battery with said electro-magnets.

3. In a regulator for musical instruments, two independently traveling music sheets each provided with perforations arranged in pairs consisting of an elongated and a short perforation; electrically operated clutches adapted to control the movement of said music rolls; pneumatically actuated mechanism governed by said perforations arranged to control the circuits whereby

said clutches are operated; and pneumatically operated brake mechanism adapted to engage said clutch mechanism when one of the music sheets is stopped.

4. In a regulator for musical instruments, two independently traveling music sheets each provided with perforations arranged in pairs consisting of a long and a short perforation; said long perforations projecting beyond the extremities of the short perforations; tracker-boards over which said music sheets are arranged to travel, said tracker-board having ducts with which said perforations register; a suction air chamber; pneumatics in said air chamber into which said ducts open; for each of said music sheets a take-up roll; a gear secured thereto; a shaft; a pinion secured thereto meshing with the gear on the take-up roll; a sprocket wheel revoluble upon said shaft; an electro-magnet secured to said wheel; a metallic disk secured to said shaft and forming an armature for said electro-magnet; a battery; an electric line having two stationary contacts therein connecting one pole of said battery to said electro-magnet; a second electric line connecting the other pole of said battery with said electro-magnet; a movable disk between said stationary contacts and adapted to connect the same; pneumatic means for controlling said movable disk governed by the perforations in the music sheets, whereby the circuits through said electro-magnets are made and broken; and means to operate said sprocket wheels.

In witness that I claim the foregoing I have hereunto subscribed my name this 21st day of July, 1904.

WILLIAM B. FLEMING.
